UNITED STATES PATENT OFFICE.

WILLIAM H. GORDENIER, OF ST. PAUL, MINNESOTA.

DESIGN FOR AN AIRPLANE TOY.

Application filed May 17, 1928. Serial No. 26,722. Term of patent 3½ years.

To all whom it may concern:

Be it known that I, WILLIAM H. GORDENIER, a citizen of the United States, residing at St. Paul, in the county of Ramsey and State of Minnesota, have invented a new, original, and ornamental Design for an Airplane Toy, of which the following is a specification, reference being had to the accompanying drawing, forming part thereof.

In the accompanying drawing,—

Fig. 1 is a top or plan view, Fig. 2 is a front elevation and Fig. 3 is a side elevation of an airplane toy, showing my new design.

I claim:

The ornamental design for an airplane toy, as shown.

WILLIAM H. GORDENIER.
